PAGE 2

Fig. 2

Fig. 3

Fig. 4

FIG. 5

FIG. 1 is an isometric view of a fluid operated carton closer showing my new design.

FIG. 2 is a side elevational view thereof.

FIG. 3 is a rear elevational view thereof.

FIG. 4 is a front elevational view thereof.

FIG. 5 is a plan view thereof.

The air hose is fragmentarily shown in FIGS. 1 and 2 for convenience of illustration.

I claim:

The ornamental design for a fluid operated carton closer or similar article, as shown and described.
